UNITED STATES PATENT OFFICE.

JOHN HERMAN AHLERS, OF PENDER, NEBRASKA.

ATTACHMENT FOR MIXING CHAMBERS.

Application filed April 18, 1922. Serial No. 555,498.

To all whom it may concern:

Be it known that I, JOHN HERMAN AHLERS, citizen of the United States, residing at Pender, in the county of Thurston and State of Nebraska, have invented certain new and useful Improvements in Attachments for Mixing Chambers, of which the following is a specification.

This invention relates to an improved attachment for the mixing chambers of Fordson tractors and seeks, as one of its principal objects, to provide a device which will, when the engine of a Fordson tractor is started or stopped relieve back pressure in the mixing chamber of the engine to prevent overflow of the engine air washer.

A further object of the invention is to provide a device which will make it possible to easily prime the tractor engine when starting.

And the invention has as a still further object to provide a device which may be readily applied to the mixing chamber of a tractor in lieu of the usual cover plate for said chamber.

Other and incidental objects will appear hereinafter.

In the drawings:

Figure 1 is a sectional view through the mixing chamber of a Fordson tractor showing my improved device applied, and

Figure 2 is a perspective view of the device in detail.

Referring now more particularly to the drawings, it will be seen that I have shown my improved device in connection with a conventional mixing chamber of a Fordson tractor. The chamber is indicated at 10, this chamber being provided with an inlet nipple 11 and being formed at its lower side with an outlet pipe 12. Fitting in the chamber axially thereof is an air valve guide 13 and surrounding said guide is an air valve 14 cooperating with a flange 15 depending into the casing. Mounted in the nipple 11 is a valve 16. All of this structure is conventionally shown, being typical of the usual mixing chamber as found upon a Fordson tractor. In this connection, it may be noted that the nipple 11 is connected by a suitable pipe with the air washer of the tractor, through which air washer the primary supply of air is drawn to the mixing chamber but since said air washer forms no part of the present in-

vention, it has not been shown. In carrying the invention into effect, I provide a cover plate 17 which is formed to fit the chamber at its upper end and takes the place of the usual cover plate for the chamber. The cover plate 17 is secured by the customary cap bolts 18 provided in connection with the usual cover and rising from the cover 17 is a U-shaped valve guide 19. This valve guide is formed at its ends with lugs 20 seating flat against the cover and threaded through said lugs are screws 21 detachably connecting the guide to the cover. Threaded or otherwise mounted upon the upper horizontal portion of the guide is a guide sleeve 22 lying axially of an opening 23 in the cover and normally closing said opening is a valve 24, the wall of the opening being beveled to seat the valve. Rising from the valve is a stem 25, slidably received through the sleeve 22 so that the stem coacts with the sleeve for guiding the valve, the valve normally gravitating to closed position and, as will be observed, the stem projects at its upper end above the guide 19 so that said stem may be readily grasped for opening the valve. Depending from the cover 17 at opposite sides of the opening 23 therein, are stops 26 having reduced upper terminals extending through the cover and upset for connecting the stops with the cover while, at their lower ends, said stops are formed with laterally directed lugs 27 to engage the upper end edge of the air valve guide 13 binding said guide in position.

In operating a Fordson tractor, overflow of the air washer of the tractor engine is often experienced when the engine is started or stopped, due to back fire of the engine or back lash of one of the engine pistons, which sets up a back pressure through the mixing chamber of the engine into the air washer, pressing down the float thereof and raising the water in the air washer which is thus caused to overflow. However, as will now be understood in view of the preceding description, the valve 24 will, when back pressure enters the mixing chamber, be automatically lifted so that the back pressure in said chamber will be permitted to escape therefrom and consequently will not reach the air washer. Accordingly, the valve will function to automatically prevent overflow of the air washer. It has been deemed unnecessary to show the air washer since such

air washer is a conventional part of a Fordson tractor. Under normal circumstances, the valve will not only be held closed by gravity but by suction in the mixing chamber as well so that leakage of air past the valve into the chamber will be prevented. In cold weather, the valve may be lifted when a quantity of gasoline or other suitable priming fluid may be introduced into the mixing chamber 10 for priming the engine so that the engine may thus be readily started. I accordingly provided a particularly efficient device for the purpose set forth and, as will now be appreciated, 15 a device which may be readily applied.

Having thus described the invention, what is claimed as new is:

1. The combination with a mixing chamber having an air valve guide therein, and 20 an air valve associated with said guide within the chamber, of a closure for the chamber, means carried by the closure to coact with said guide for securing the guide in position, and a relief valve carried by the 25 closure.
2. The combination with a mixing chamber having a removable air valve guide

therein, and an air valve associated with said guide within the chamber, of a closure for the chamber, depending stops carried by 30 the closure to engage the upper edge of the guide holding the guide in position, and a vent valve carried by the closure.

3. The combination with a mixing chamber open at its upper end and provided with a lateral inlet nipple and at the bottom thereof with an outlet nipple, and an air valve guide fitting in the chamber and removable at the upper end thereof, of a 35 plate secured to the upper end of the chamber closing the chamber, stops depending from the plate and provided at their lower ends with laterally directed lugs overhanging the upper edge of the valve guide securing the guide against upward displacement, 40 the plate being provided with a vent opening, a yoke upstanding from the plate straddling said opening, and a vent valve sustained by said yoke normally closing 45 said opening.

In testimony whereof I affix my signature.

JOHN HERMAN AHLERS. [L. S.]
